PERMANENT WAVING DEVICE

William H. Brown, Bedford, Ohio, assignor to
 Adolf Kietz, Bellevue, Wash., and Phil D.
 Spaeth, Cincinnati, Ohio

Application February 24, 1937, Serial No. 127,476

2 Claims. (Cl. 219—24)

This invention relates to permanent waving and has particular reference to electrolytic heating of wound curls.

The principal object of the invention is to prevent corrosion between the permanent contact element carried by the clip which supplies current for heating the curl and to accomplish this by placing a temporary or removable and renewable contact in such relation as to seal off the vapors from the permanent contact.

Other objects are the provision of a peculiarly effective form of renewable contact element and a simple and effective means for mounting and removing the same.

Other and more limited objects will be in part apparent and in part pointed out in connection with the accompanying drawing wherein Fig. 1 is an elevation of a permanent waving assembly including protective clamp, curler rod, electrolytic pad and clip; Fig. 2 is a transverse section taken through the assembly of Fig. 1; Fig. 3 is a fragmentary central section of the clip alone looking from the center; Fig. 4 is a section corresponding substantially to either of the lines 4—4 of Fig. 3; Fig. 5 is a section on the line 5—5 of Fig. 3 and Fig. 6 is an exploded view showing the parts in the same section as in Fig. 5.

Referring now to the drawing, the numeral 10 indicates a protector clamp which may be of conventional construction such as used in the art of Croquignole waving. Carried by suitable cradle elements 11 on the protector clamp 10 is a curler rod 12 also of conventional construction. Surrounding the curler rod, as best seen in Fig. 2, is a wound strand of hair 13 and surrounding the hair 13 is the electrolytic pad indicated generally by the numeral 14. This pad consists of a liquid sustaining sheet 15 which may be composed of cotton flannel or similar fabric and to the outer surface of which are secured electrodes 16 which may be composed of sheet metal, preferably metal foil. The joint between the electrodes 16 may be covered by an element 17 which may be of wax paper or the like to prevent excessive evaporation at that point.

Attached in gripping relation to the wound curl and electrolytic pad is a clip which in the present instance is a two-part sectional clip having jaws 18 secured together by a spring connector 19 adapted to urge them toward each other. Each of the jaws 18 has formed therein a depression 20 which is extended at the ends into openings 21 extending completely through the jaws. These openings are provided with shoulders or ledges 22 upon which are seated sealing gaskets 23 in

surrounding relation to the openings 21. Between the openings 21 is a permanent contact element 24 which is received in a slight extension of the depression 20 so that it may be said to be embedded in the jaw element 18 at the bottom of the depression 20. Preferably the thickness of the element 24 and the depth of the depression receiving the same are so related that the element 24 projects very slightly above the adjacent surface of the jaw element. It is to be understood, 10 of course, that the jaw element is composed of electrically non-conductive material which preferably also has good heat insulating properties. The element 24 extends beyond the depression 20 at both sides, as is clearly brought out in Fig. 2, 15 and this serves to anchor the same in position. Conductors 25 are connected to the element 24 and extend from the clip to a suitable source of current.

Extending through the element 24 and preferably embedded in the jaw element 18 in such manner as not to depend entirely on the element 24 for support is a stud 26 which projects outwardly beyond the depression 20. Received in the depression 20 is a removable and renewable 25 contact element 27 which is provided with embossed projections 28 having end faces adapted to engage and conform to a curl and adapted to extend through sealing gaskets 23 and through the openings 21 whereby to contact the electrode 30 elements 16. The element 27 is provided with an opening 29 adapted to receive the stud 26. The element 27 is preferably constructed of very thin sheet metal which may be stamped to the proper shape and which preferably is either of fairly 35 good non-corrosive properties or plated with a metal of such properties. This element may be of thin copper or tin plate. The element 27 is held in position by means of a holding element 30 having an opening 31 adapted to be received 40 on the stud 26 and projections 32 adapted to be received in the concavities of the embossed projections 28. A suitable nut 33 having an electrically non-conductive exterior covering is received on the stud 26 in threaded relation and 45 holds the elements assembled as indicated in Fig. 5.

From the foregoing it will be obvious that the problem of corrosion in electrolytic heating of wound curls in permanent waving is met by the 50 periodic discarding of an inexpensive element and that the device is well adapted for its intended purpose. While I have shown and described the present preferred embodiment, I wish it understood that the invention may be realized in dif- 55

ferent structures and that I am limited only in accordance with the appended claims.

Having thus described my invention, what I claim is:

- 5 1. In a clip for electrolytic heating of wound
curls in permanent waving, an electrode contact
carrying element having a depression formed in
one face thereof and an opening extending from
the bottom of said depression through said ele-
ment, a permanent contact in said depression, a
removable electrode contact received in said de-
pression and having a projection extending
through said opening, sealing means surround-
ing said projection for prevention of passage of va-
10 pors through said opening and a retaining ele-
ment overlying said electrode and substantially
closing said depression.
- 15 2. In a clip for electrolytic heating of wound
curls in permanent waving, an electrode contact
carrying element adapted to engage a curl and
having an opening extending therethrough, a
permanent contact secured to said element, a
sheet metal removable contact having an em-
bossed portion extending through said opening
and adapted to engage a curl, means for holding
said removable contact in engagement with said
permanent contact and means providing a seal 10
for preventing liquid from passing from said em-
bossed portion along said removable contact to
said permanent contact.
